UNITED STATES PATENT OFFICE.

WILLIAM F. GOODHUE, OF MILWAUKEE, WISCONSIN, ASSIGNOR OF ONE-HALF TO CHRISTOPHER PAULUS, OF SAME PLACE.

SEWAGE SEPARATING AND PURIFYING APPARATUS.

SPECIFICATION forming part of Letters Patent No. 478,539, dated July 5, 1892.

Application filed October 8, 1891. Serial No. 408,092. (No model.)

To all whom it may concern:

Be it known that I, WILLIAM F. GOODHUE, of Milwaukee, in the county of Milwaukee and State of Wisconsin, have invented certain new and useful Improvements in Sewage Separating and Purifying Apparatus; and I do hereby declare that the following is a full, clear, and exact description of the invention, which will enable others skilled in the art to which it pertains to make and use the same, reference being had to the accompanying drawings, and to the letters of reference marked thereon, which form a part of this specification.

15 The main object of my invention is to forcibly and continuously separate by mechanical means the solid from the liquid constituents of sewage and other similar matter.

It consists, essentially, of a cylinder or 20 chamber provided with a reciprocating strainer and with suitable connections and valves, whereby the sewage is fed into said cylinder or chamber and the separated solid and liquid constituents are discharged there- 25 from into suitable receptacles or conduits.

In the accompanying drawings like letters designate the same parts in the several figures.

Figure 1 is a partial side elevation and 30 vertical axial section of my improved apparatus. Fig. 2 is a vertical cross-section through one of the separating-cylinders, and Fig. 3 is a detail view of one of the sludge-valves with its actuating mechanism.

35 A A' represent two horizontal cylinders arranged in line with each other. They are provided with screens B B', fitted and arranged therein in the manner of pistons. They are mounted and fixed upon a piston- 40 rod b, which passes through stuffing-boxes in both ends of said cylinders and through an intermediate steam-cylinder C, within which is fitted and mounted upon said piston-rod a piston D. These several cylinders are connected and held firmly in place by tie-rods c c. The cylinders A A' are provided at the upper side of their outer ends with ports a a, which are connected with the supply pipe or conduit E by branches E' E'. These cylinders are also provided on the under side with ports a' a' for the discharge of the sludge at the outer ends and at their inner ends with

ports a² a² for the discharge of the liquid portion of the sewage from which the sludge has been separated. The ports a² are connected with a discharge-pipe F by branches F' F', and the ports a' open into or are connected with suitable conduits or receptacles.

The branches E' E', through which the sewage is fed to the cylinders A A', are provided with valves e e', which are operated by mechanism so arranged as to admit the sewage alternately into said cylinders when the screen-pistons B B' are at or near the inner ends of their strokes. For this purpose I provide the valve-stems with crank-arms e² e², which are connected with slotted blocks e³ e³, adjustably mounted upon a horizontally-sliding rod e⁴, which is supported in suitable bearings e⁵. This rod is reciprocated by means of a lever 70 G, fulcrumed to a block g, which is adjustably mounted upon one of the tie-rods c or upon any other suitable support. This lever is provided with longitudinal slots at the ends, by means of which it is pivoted at its lower end to a pin on a collar g', adjustably mounted upon the piston-rod b, and at its upper end to a pin on a sleeve adjustably mounted upon the reciprocating valve-rod e⁴.

The valve of the engine by which the separator-screens are operated may be actuated by means of the same lever G. For this purpose I provide the valve-rod H with an adjustable collar h and connect it by a rod h' with said lever. To give the proper movement to the 85 valve, the connecting-rod h' is pivoted by a crank-pin in a longitudinal slot in said lever G. To allow for the arc motion of the crank-arms e² in connecting them with the reciprocating rod e⁴, I provide the free ends of said 90 crank-arms with crank-pins, which engage with vertical slots formed for their reception in lateral projections on the adjustable collars or blocks e³.

The conduits or passages into which the 95 discharge-ports a' open are provided with transverse slides K K', constituting the sludge-valves. These valves are normally closed by means of springs k and are opened against the opposing force of said springs by 100 means of hooks l l, pivoted to depending arms L L, mounted upon the projecting ends of the piston-rod b, and by blocks k' k' on the stems k² of said sludge-valves, the hooks l being ar-

ranged in their outward movement to engage with said blocks and to release the same when the valves are fully opened by striking fixed projections k^3 , as shown in Fig. 3. As soon as the hooks l are released from the blocks k' the valves are instantly closed by the action of the springs k .

My improved apparatus operates as follows: The sewage entering the apparatus through the supply-pipe E is admitted alternately to the receiving ends of the cylinders A A' by the valves e e' . When the piston D and the screens B B' are moved to the left into the position in which they are shown in the drawings, the valve e is closed and the valve e' is opened, thereby admitting sewage to the outer end of cylinder A' through the port a . In this position of the separating-screens the sludge-valve K' is closed, while the valve K at the opposite end of the apparatus is opened. Now as the piston D is reversed and moves the screens B B' to the right the valve e will be opened and the valve e' will be closed. The screen b' , advancing against the sewage contained in cylinder A' , permits the liquid portions thereof to pass through it into the inner end of the cylinder, whence it escapes through the port a^2 and branch E' into the discharge pipe or conduit F , the solid constituents of the sewage being carried to the outer end of the cylinder, and the greater part of the liquid expressed therefrom is as the screen B' nears the end of its stroke discharged through the port a' by the opening of the sludge-valve K' , in the manner hereinbefore described.

While the latter operation is going on in the cylinder A' the cylinder A is being filled with sewage, and thus the operation goes on continuously, first one and then the other cylinder being filled and the sludge being separated and discharged alternately in opposite ends of the apparatus.

Various changes may be made in the details of my apparatus within the scope of my invention. Where apparatus of small capacity is sufficient, a single-acting separator, like or similar to one end of the apparatus hereinbefore shown and described, may be employed.

While I have shown and described my apparatus as specially designed for operating upon sewage, I do not wish to be understood as limiting myself thereby to such particular use, inasmuch as the apparatus may be applied with advantage to the separation of the solid and liquid portions of a variety of matter other than sewage.

I claim—

1. In a sewage-separator, the combination of a cylinder or chamber connected at one end with a sewage-supply and having a sludge-discharge port at the same end and a liquid-discharge port at the opposite end, and a reciprocating screen-piston adapted to said cylinder or chamber, substantially as and for the purposes set forth.

2. In a sewage-separator, the combination

of two cylinders or chambers connected at one end with the sewage-supply and having discharge-ports for the sludge and liquid at opposite ends thereof, reciprocating screens adapted to work within said cylinders or chambers, and valves adapted to admit the sewage alternately to said cylinders or chambers, substantially as and for the purposes set forth.

3. In a sewage-separator, the combination of two cylinders placed in line with each other and provided with reciprocating screens adapted to work within the same, a steam-cylinder provided with a piston connected with the rod upon which said screens are mounted and arranged to actuate the same, a sewage-supply pipe or conduit connected with said separator-cylinders, valves arranged to admit the sewage alternately thereto, liquid and sludge ports and connections at opposite ends of the cylinders, and sludge-valves arranged to be opened at the proper time to discharge the sludge from said cylinders, substantially as and for the purposes set forth.

4. In a sewage-separator, the combination of a separating chamber or cylinder provided with a reciprocating screen adapted to work therein and having sewage-supply and sludge-discharge ports at one end and a liquid-discharge port at the opposite end, a supply-valve, and a sludge-valve with mechanism arranged to open and close the same alternately, substantially as and for the purposes set forth.

5. In a sewage-separator, the combination of a separating-cylinder, a steam-cylinder placed in line therewith, a piston-rod common to said cylinders, a piston mounted upon said rod in the steam-cylinder, and a screen mounted thereon in the separator-cylinder, a sewage-supply connection with one end of the separator-cylinder, a liquid-discharge connection with the opposite end of said cylinder, and a sludge-discharge valve communicating with the feed end of said separator-cylinder, substantially as and for the purposes set forth.

6. In a sewage-separator, the combination of a pair of separator-cylinders and an interposed steam-cylinder placed in line with each other and provided with a common piston-rod, a piston mounted upon said rod in the steam-cylinder, and screens mounted thereon in the separator-cylinders, a sewage-supply pipe connected by branches with said separator-cylinders, a liquid-discharge pipe or conduit connected by branches with the opposite ends of said cylinders, feed-valves placed in the branches of the supply pipe or conduit, and connections between said valves and the piston-rod, whereby they are alternately opened and closed and sewage is admitted first into one and then the other separator-cylinder, substantially as and for the purposes set forth.

7. In a sewage-separator, the combination of a separator-cylinder and a steam-cylinder located in line with each other and provided

- with a common piston-rod, a piston mounted upon said rod in the steam-cylinder, and a screen mounted thereon in the separator-cylinder, a supply-pipe connected with one end 5 of the separator-cylinder and provided with a feed-valve, a liquid-discharge pipe or conduit leading out of the opposite end of said cylinder, and connections between said feed-valve and piston-rod, whereby the sewage is 10 intermittently admitted into said separator-cylinder, substantially as and for the purposes set forth.
8. In a sewage-separator, the combination of a cylinder provided with a reciprocating 15 piston-rod and a screen mounted thereon within said cylinder, a sewage-supply connection provided with a feed-valve communicating with one end of said cylinder, a sludge-discharge port leading out of the same end of 20 the cylinder and provided with a valve, and connections between the piston-rod and feed and discharge valves, whereby the latter are alternately opened, substantially as and for the purposes set forth.
9. In a sewage-separator, the combination 25 of a separating cylinder or chamber provided with a reciprocating rod, a screen mounted upon said rod within said cylinder, a supply connection with one end of said cylinder, provided with a feed-valve, a sludge-discharge port opening out of the same end of the cylinder and provided with a valve, a spring normally closing said valve, and a hook pivoted to the piston-rod and arranged to engage with 30 a projection on the sludge-valve stem so as to open said valve at the proper time, substantially as and for the purposes set forth.
10. In a sewage-separator, the combination 35 of a separating cylinder or chamber provided with a reciprocating piston-rod, a screen mounted upon said rod within said cylinder, a sludge-discharge port opening out of said cylinder and provided with a slide-valve, a spring normally closing said valve, a hook 40 pivotally connected with said piston-rod and arranged to engage with a projection on said valve-stem and to open said valve, and a relatively-fixed projection by which said hook is tripped and released from the projection on 45 the valve-stem at the proper point, substantially as and for the purposes set forth.
11. In a sewage-separator, the combination of separator-cylinders, an interposed steam-cylinder in line therewith, a piston-rod upon which the steam-piston is mounted, screens 55 mounted upon said piston-rod within the separator-cylinders, sewage-supply connections communicating with said cylinders and provided with feed-valves, a sliding rod connected with crank-arms on the feed-valve stems, and a lever pivotally connected at one end with the piston-rod and at the opposite end with said sliding valve-rod, substantially as and for the purposes set forth.
12. In a sewage-separator, the combination, 65 with a steam-cylinder provided with a piston and piston-rod, of a separator-cylinder in line therewith, a screen mounted upon said piston-rod within the separator-cylinder, a sewage-supply pipe provided with a feed-valve, 70 connected with one end of the separator-cylinder, a reciprocating rod parallel with said piston-rod and connected with a crank-arm on the feed-valve stem, a lever fulcrumed to a suitable support and pivotally connected with the piston-rod on the one hand and said sliding valve-rod on the other hand, and a rod connecting said lever with the stem of the steam-valve, substantially as and for the purposes set forth.
13. In a sewage-separator, the combination 75 of a cylinder provided with an actuating-piston and piston-rod, a separator-cylinder, a screen mounted upon said piston-rod within said separator-cylinder, a sewage-supply connection with one end of the separator-cylinder, provided with a feed-valve, a reciprocating rod parallel with the piston-rod, adjustably connected with a crank-arm on the feed-valve stem, and a lever fulcrumed to an adjustable support and adjustably pivoted on opposite sides thereof to said piston-rod and reciprocating valve-rod, substantially as and for the purposes set forth.

In testimony that I claim the foregoing as 95 my own I affix my signature in presence of two witnesses.
